[57] CLAIM

The ornamental design for a seat for a cooling fan of a heat sink assembly, as shown.

DESCRIPTION

FIG. 1 is a front elevational view thereof;
FIG. 2 is a rear elevational view thereof;
FIG. 3 is a left elevational view thereof;
FIG. 4 is a right elevational view thereof;
FIG. 5 is top plan view thereof;
FIG. 6 is a bottom plan view thereof;
FIG. 7 is a front-right-top perspective view of a seat for a cooling fan of a heat sink assembly, showing my new design; and,
FIG. 8 is a right-top-front perspective view thereof, with the broken-line of the cooling fan being for illustrative purposes only and forming no part of the claimed design.
